UNITED STATES PATENT OFFICE.

EUGENE COOK, OF KALAMAZOO, MICHIGAN.

LIFTING-JACK.

SPECIFICATION forming part of Letters Patent No. 787,435, dated April 18, 1905.

Application filed June 6, 1904. Serial No. 211,344.

To all whom it may concern:

Be it known that I, EUGENE COOK, a citizen of the United States, residing at the city of Kalamazoo, county of Kalamazoo, State of Michigan, have invented certain new and useful Improvements in Lifting-Jacks, of which the following is a specification.

This invention relates to improvements in lifting-jacks.

10 The main object of this invention is to provide an improved lifting-jack which may be tripped with comparative ease even while sustaining a heavy load.

Further objects and objects relating to structural details will definitely appear from the detailed description to follow.

I accomplish the objects of my invention by the devices and means described in the following specification.

20 The invention is clearly defined, and pointed out in the claims.

A structure embodying the features of my invention is clearly illustrated in the accompanying drawings, forming a part of this 25 specification, in which—

Figure 1 is a side elevation view, partially in section, to show the arrangement of parts of a structure embodying the features of my invention. Fig. 2 is a detail sectional view 30 taken on line 2 2 of Fig. 1 looking in the direction of the little arrows at the ends of the section-lines, showing the relation of the trip-hook F to the holding-pawl. Fig. 3 is an enlarged side elevation view of the trip-hook F 35 in an inverted position.

In the drawings similar letters of reference refer to similar parts throughout the several views.

Referring to the drawings, A is the frame, 40 and B is the lifting-bar, the lifting-bar being provided with suitable ratchet-teeth on one side. The shank C of the operating-lever is pivoted on the frame A. A lifting-pawl E is pivotally secured on the inner end of the shank C.

45 A holding-pawl D is supported above the lifting-pawl by a suitable pivot on the frame A. This holding-pawl is adapted to retain the lifting-bar during the downward movements of the lifting-pawl.

50 In operation the lifting-bar B is elevated by

means of the lever. The pawl E engages the bar, so that when the lever is forced downwardly the bar is elevated. The retaining-pawl D engages the bar and holds it in its elevated position until released or until the lever 55 is again operated to further elevate the bar, when the operation is repeated.

A trip-hook F is pivotally secured at c to the shank C of the operating-lever for disengaging the pawls to release the lifting-bar. 60 This trip-hook is adapted to engage a laterally-projecting pin e toward the upper end of the lifting-pawl E and is also provided with a laterally-projecting lug or pin f, adapted to engage the inner face of the holding-pawl D 65 to disengage it. This lug or pin is so arranged that the pawl D is disengaged from the lifting-bar before the trip-hook acts upon the pawl E—that is, the pawls are acted upon successively.

The holding-pawl D is notched at d for the passage of the pin f, so that when the trip-hook is thrown inwardly and the operating-lever elevated it will automatically drop into place, the pin f dropping behind the pawl D. 70

75 With the trip-hook in its engaging position, as illustrated in Fig. 1, the operating-lever is forced downwardly, which, as stated, first withdraws the holding-pawl D from the lifting-bar and then the lifting-pawl E. As the 80 line of pull is comparatively direct on the end of the lifting-pawl, it is much more easily withdrawn than the holding-pawl when sustaining a full load. By this arrangement of parts I am enabled to withdraw the holding- 85 pawl while the main portion of the load is sustained by the lifting-pawl. The lifting-pawl is then withdrawn by a comparatively direct pull on the pawl, as stated, so that I am enabled to trip the jack while under a heavy 90 load with comparative ease. While the load is being lifted, the trip is thrown outwardly against the rest c' on the shank, as is indicated by dotted lines in Fig. 1.

The parts of my improved lifting-jack are 95 very simple to construct and durable in use. I have illustrated and described my invention in the form preferred by me on account of the simplicity and economy of structure, although I am aware that the same may be varied in 100

structural details without departing from my invention.

Having thus described my invention, what I claim as new, and desire to secure by Letters 5 Patent, is—

1. In a lifting-jack, the combination of a frame; a lifting-bar; an operating-lever; a lifting-pawl pivotally secured to the inner end of said operating-lever and having a laterally-projecting pin toward its upper end; a holding-pawl having a notch in one edge thereof pivotally supported on said frame; a trip-hook pivotally secured to said lever adapted to engage the laterally-projecting pin on the lifting-pawl and having a laterally-projecting pin thereon adapted to pass through the said notch in said holding-pawl and engage the inner face thereof, said pin being so arranged as to withdraw said holding-pawl from engagement with said lifting-bar before said lifting-pawl is acted upon, for the purpose specified.
2. In a lifting-jack, the combination of a frame; a lifting-bar; an operating-lever; a lift-

ing-pawl pivotally secured to the inner end of said operating-lever; a holding-pawl pivoted 25 on said frame; a trip member pivotally secured to said lever adapted to engage said pawls successively, whereby said holding-pawl is withdrawn from engagement with said lifting-bar before said lifting-pawl is acted upon, for the 30 purpose specified.

3. In a lifting-jack, the combination of a lifting-bar; an operating-lever; a lifting-pawl pivotally secured to the inner end of said operating-lever; a holding-pawl coacting with 35 the said lifting-pawl; a trip member pivotally secured to said lever, adapted to engage said pawls successively whereby they are withdrawn successively from engagement with the said lifting-bar, for the purpose specified. 40

In witness whereof I have hereunto set my hand and seal in the presence of two witnesses.

EUGENE COOK. [L. s.]
